ABSTRACT OF THE DISCLOSURE

A tower structure including a plurality of sections with weight elements therein disposed upon a platform which is adapted to have its angle of support selectively changed by an adjustment member. The tower will tip over or remain standing depending upon the angle of the support platform. The center of gravity of the tower may be varied by the selective rotating of the weighted sections and thereby change the angle at which the tower may tilt before it begins to tip.

This invention is a game or an amusement device involving the tower of Pisa. The tower of Pisa as is well known, has leaned for many years at a substantial angle to the vertical without falling. This game thus challenges the player to see how much he can tilt the miniature tower without it falling. Scoring indicia is provided to indicate the amount of tilt as an adjustment member is operated which pivots a support base portion on which the tower rests. The tower is made up of a plurality of sections stacked end to end with certain of the sections having weights or ballasts off their longitudinal center such that when they are placed in the tower they will change the tower's center of gravity and accordingly varying the angle of tilt that will cause the tower to tip.

These and other features and advantages of this invention will become readily apparent to those skilled in the art upon reference to the following description when taken into consideration with the accompanying drawings, wherein:

FIG. 1 is a perspective view of the amusement device of this invention;

FIG. 2 is a cross sectional view taken along line 2—2 in FIG. 1;

FIG. 3 is a cross sectional view taken along line 3—3 in FIG. 1;

FIG. 4 is a fragmentary perspective view of a tower section illustrating the ballast inside thereof;

FIG. 5 is a fragmentary perspective exploded view of the base with the pivotal base portion for supporting the tower; and

FIG. 6 is a perspective view of the adjustment slide member which when operated selectively varies the angle of tilt of the tower.

The amusement device of this invention is generally referred to in FIG. 1 by the reference numeral 10 and includes a support base 12 on which a tower 14 is positioned.

The tower 14 which simulates the leaning tower of Pisa is made up of a plurality of intermediate sections 16 stacked one on top of the other. Each of the tower sections 16 has the same diameter and shape. The base section 18 is the same diameter as the section 16 but is taller like in the actual tower of Pisa. The uppermost or top cap section 20 is substantially smaller in diameter. Each of the top sections has an annular outer peripheral flange 22 and a top end wall 23 for receiving the lower open end of a tower section. Each of the sections includes an inner concentric flange 24 for receiving the lower open end of the smaller top section 20.

A weight or ballast element 26 is provided on the inner side wall of each of the sections. Accordingly, each time

2

the sections are stacked the center of gravity of the tower will be different. The weights may be of different shapes and located as desired off the center axis of the sections.

The section 12 includes an opening 30 in which a pivotal base portion 32 is positioned. The pivotal base portion 32 has a shaft 34 extending along one end and is snapped into semicylindrical recesses 36 formed in the top wall 37 on opposite sides of the opening 30. The pivotal base portion 32 is substantially semicircular in shape and thus includes an outer rounded edge 38. A rearwardly extending tab element 40 is provided for engaging the bottom side of the top base wall 37 adjacent the rear end to prevent the pivotal base portion or door 32 from pivoting too far downwardly through the opening 30.

A slide adjustment member 50 extends between a pair of parallel vertical side walls 52 on the underside of the top wall 37 of the base 12. A slide member 50 includes a flat cam portion 54 having an upwardly curved inner end 56 sliding over a supporting table top or the like. The opposite end of the cam portion 54 is integral with a downwardly extending portion 58 which is connected to a horizontally disposed flat portion 58 extending outwardly through an opening in the front wall 59 of the base 12. A finger actuating upstanding tab 60 is provided on the outer end edge of the portion 58. Scoring indicia 62 is provided along the side edge of the portion 58 and may be read by noting the marking closest to the front end wall 59 of the base 12. A downwardly extending tab 70 is provided on opposite sides of the cam portion 54 and frictionally engage the walls 52 of the base 12 to hold the slide adjustment member 50 against accidental movement.

It is thus seen that the outer free rounded edge 38 of the pivotal base portion or trap door 32 engages the outer surface of the cam portion 54 and as the slide member 50 is moved inwardly and outwardly the angle of the trap door 32 is varied consequently causing the tower to tilt back and forth as seen for example by the solid lines and dash line positions in FIG. 3. The object of the game of course is to pull the slide member 50 as far outwardly as possible thereby tilting the tower as much as possible without it falling off of the trap door 32. The farther the slide member 50 is pulled outwardly the higher the number will be that is registered on the portion 58.

It is to be appreciated that the assembling of the tower sections after the tower has fallen will very unlikely result in the same arrangement and thus giving the tower a different center of gravity and consequently changing the angle of tower tilt that is required to tip the tower over when the slide member 50 is operated. Each time the game is operated it provides a new and different challenge since it will not operate the same twice.

Some changes may be made in the construction and arrangement of my amusement device without departing from the real spirit and purpose of my invention, and it is my intention to cover by my claims, any modified forms of structure or use of mechanical equivalents which may be reasonably included within their scope.

I claim:

- An amusement device, comprising,
a base member,
a portion of said base member being pivotal about a horizontal axis,
a tower positioned on said pivotal base portion,
adjustment means for selectively pivoting said pivotal base portion,
said tower being comprised of a series of separate sections stacked together,
certain of said sections having a center of gravity differing from certain of said other sections,

said sections having a different center of gravity having ballast means located remotely of the vertical center axis of said sections whereby rotation of said sections varies the center of gravity of said sections.

2. An amusement device, comprising,
a base member,
a portion of said base member being pivotal about a horizontal axis,
a tower positioned on said pivotal base portion,
adjustment means for selectively pivoting said pivotal base portion, and
said adjustment means including a cam portion engaging said pivotal portion,
said cam portion being movable relative to said pivotal position to pivot said pivotal portion between a substantially horizontally extending position to a downwardly extending position.

3. The structure of claim 2 and an indicator means measuring the relative movement between said cam portion and said pivotal portion.

4. The structure of claim 3 wherein said cam portion is enclosed by said base and said indicator means is connected to said cam portion and extends outwardly of said base.

5. The structure of claim 4 wherein the cam portion extends under and downwardly of the free end of said pivotal portion whereby as said adjustment means is moved outwardly of said base said free end of said pivotal portion moves downwardly along said cam portion thereby tilting said tower.

6. The structure of claim 5 wherein said adjustment means is formed from an integral member comprising said cam portion on the inner end thereof, and a downwardly extending portion connected to said indicator means and extending in a horizontal plane with an outer end portion exposed for manually operating said adjustment means.

7. An amusement device, comprising,
a base member,
a portion of said base member being pivotal about a horizontal axis,

a tower positioned on said pivotal base portion, adjustment means for selectively pivoting said pivotal base portion,
said tower being comprised of a series of separate sections stacked together, and
said pivotal base portion including a pin element extending laterally outwardly from opposite sides thereof, said base having an opening formed therein and a recess on opposite sides of said opening for receiving said pin elements whereby said base portion may pivot through said opening.

8. An amusement device, comprising,
a base member,
a tower positioned on said base portion and having a longitudinal center axis,
adjustment means for selectively tilting said base portion and said tower,
said tower being comprised of a series of separate sections stacked together, and
certain of said sections having a ballast means having a center of gravity located remotely of said longitudinal center axis whereby upon rotation of one of said sections the center of gravity of said tower will be changed.

9. The structure of claim 8 wherein said stacked sections have complementary abutting ends adapted to permit rotation therebetween to vary the center of gravity of said tower.
